ATTY.

UNITED STATES PATENT OFFICE.

CARROLL J. WEBSTER, OF LYNN, MASSACHUSETTS, ASSIGNOR TO GENERAL ELECTRIC COMPANY, A CORPORATION OF NEW YORK.

CENTRIFUGAL SWITCH.

1,022,904.

Specification of Letters Patent.

Patented Apr. 9, 1912.

Application filed July 31, 1909. Serial No. 510,513.

To all whom it may concern:

Be it known that I, CARROLL J. WEBSTER, a citizen of the United States, residing at Lynn, in the county of Essex and State of 5 Massachusetts, have invented certain new and useful Improvements in Centrifugal Switches, of which the following is a specification.

My invention relates to centrifugally-operated switches for alternating-current motors and is particularly applicable to small single-phase induction motors of the type having a starting winding which is open-circuited when the motor is up to 10 speed. Such motors have been provided heretofore with stationary collector rings concentric with the motor-shaft and a contact on each side of the motor-shaft and rotatable therewith, which bridges the collector rings at starting but when the motor is up to speed are thrown away from the collector rings by centrifugal force. Such contacts have the disadvantage that if they do not line up properly with the collector 15 rings, they will not bridge them so as to close the circuit of the starting winding when the motor is starting.

My invention consists in a novel and simple form of centrifugally-actuated switch 20 adapted for use in such a structure which does not require that the collector rings and contacts be lined up with any great care.

The various features of novelty which characterize my invention are pointed out 25 with particularity in the claims annexed to and forming a part of this specification. For a better understanding of my invention, however, reference may be had to the following description taken in connection 30 with the accompanying drawing in which—

Figure 1 shows a side elevation, partly in section, of an alternating motor, provided with a centrifugal switch arranged in accordance with my invention; Fig. 2 is an 35 enlarged end view of my centrifugal switch; and Fig. 3 is a side elevation of the switch of Fig. 2.

In the drawing, 1 represents the stator of an alternating-current motor provided with 40 a primary winding 2, arranged in the usual manner. The rotor 3 I have shown, as being provided with a squirrel cage winding of well-known construction, comprising conductors 4 and end rings 5. The pair of 45 stationary collector rings 6 are concentric

with the motor-shaft and are fastened to the motor frame but insulated therefrom. These rings are connected through suitable leads 7 to the starting winding of the motor. The pairs of contacts 8 and 8¹ are pressed 50 into engagement with the collector rings by means of the flexible tension members 9, the pair 8 being on the opposite side of the motor-shaft from the pair 8¹. Each pair of contacts is arranged side by side and are 55 electrically-connected together. The dish-shaped member 10 is fastened to the rotor of the motor and has bolted thereto two pairs of studs 11 and 11¹. Each of the contacts is pivotally mounted upon one of the studs 60 and has a slot 12 or 12¹ allowing it to move about the other stud of the pair to which the contact is pivoted. About each of these studs is an insulating bushing 13 65 upon which is mounted a sleeve 14 of brass or other good electrical conducting material for electrically connecting the contacts of each pair together. The contacts are also shown as being in contact throughout their length, which position they naturally occupy 70 as the upturned portions 15 and 15¹ of the contacts engage the turned edges of the collector rings. The flexible tension members 75 80 each connect together a contact 8 and a contact 8¹. The tension members are fastened to the ends of the contacts which are provided with the slots. The upturned portions 15 and 15¹ of the contacts are also provided to make good electrical contact with the collector rings. 85

When the motor is starting the collector rings 6 are connected together by the contacts 8 and 8¹ so as to close the circuit of the starting winding. When the motor is up 90 to speed the contacts 8 and 8¹ are thrown away from the collector rings by centrifugal force, overcoming the tension of the tension members 9 so as to open the circuit of the starting winding. 95

I do not desire to limit myself to the particular construction and arrangement of parts shown, but aim in the appended claims to cover all modifications which do not depart from the spirit and scope of my invention. 100

What I claim as new and desire to secure by Letters Patent of the United States, is,

1. In an alternating-current motor, stationary collector rings concentric with the motor-shaft, a pair of studs rotatable with 110

the motor-shaft, a pair of contacts electrically connected together and arranged side by side, each of said contacts being pivotally mounted on one stud and having a slot 5 allowing it to move about said other stud, and flexible tension members for pressing said contacts into engagement with the collector rings.

2. In an alternating-current motor, stationary collector rings concentric with the motor shaft, a pair of studs rotatable with the motor shaft, a pair of contacts electrically connected together and arranged side by side, each of said contacts being pivotally mounted on one stud and having a slot 10 allowing it to move about said other stud, flexible tension members for pressing said contacts into engagement with the collector rings, and insulating bushings insulating 15 said contacts from said studs.

3. In an alternating-current motor, stationary collector rings concentric with the motor shaft, two pairs of contacts pivotally mounted and rotatable with the motor shaft, 25 each pair of contacts being electrically connected together and arranged side by side, one pair of contacts being on the opposite side of the motor-shaft from the other pair, and two tension members, one tension member connecting together a contact of each 30 pair and the other tension member connecting together the other contacts of each pair so as to press them against said collector rings when the motor is starting.

35 4. In an alternating-current motor, stationary collector rings concentric with the motor-shaft, two pairs of studs rotatable with the motor-shaft, two pairs of contacts, the contacts of each pair being electrically 40 connected together and arranged side by

side, one pair of contacts being on the opposite side of the motor-shaft from the other pair, each of said contacts being pivotally mounted on one stud and having a slot allowing it to move about the other stud of the 45 pair to which said first-mentioned stud belongs, and two tension members, one tension member connecting a contact of each pair and the other tension member connecting the other contacts of each pair so as to press them against said collector rings when the motor is starting.

5. In an alternating-current motor, stationary collector rings concentric with the motor-shaft, two pairs of studs rotatable 55 with the motor shaft, two pairs of contacts, the contacts of each pair being arranged side by side, one pair of contacts being on the opposite side of the motor shaft from the other pair, each of said contacts being 60 pivotally mounted on one stud and having a slot allowing it to move about the other stud of the pair to which said first-mentioned stud belongs, two tension members, one tension member connecting a contact of 65 each pair and the other tension member connecting the other contacts of each pair so as to press them against said collector rings when the motor is starting, insulating bushings on said studs and electrically conducting sleeves on said bushings for electrically connecting said contacts together.

In witness whereof, I have hereunto set my hand this twenty-eighth day of July, 1909.

CARROLL J. WEBSTER.
